Edward G. Roe, 19 Orchard St.,
Pleasantville, N.Y. 10570

Filed June 24, 1971, Ser. No. 156,580

Term of patent 14 years

Int. Cl. D21—02
U.S. Cl. D34—5 GT

FIG. 1 is a top plan view of my new golf tee and tethered weight.

FIG. 2 is a rear elevation thereof showing my new design.

FIG. 3 is a front elevation of the golf tee and tethered weight.

FIG. 4 is one side elevational view of the tee portion, the other side being substantially the same.

FIG. 5 is a section taken through line 5—5 of FIG. 1.

FIG. 6 is a bottom plan view of the golf tee and shows the shape of the tethered weight.

FIG. 7 is a top plan view of my golf tee shown in FIG. 1 with the wall of the cup inverted to afford a lower hitting surface.

FIG. 8 is a side elevation of the golf tee of FIG. 7.

I claim:

The ornamental design for a golf tee and tethered weight, as shown and described.
